CIRCUIT BREAKER

Donald B. Robinson, Detroit, Mich., assignor, by mesne assignments, to I-T-E Circuit Breaker Company, Philadelphia, Pa., a corporation of Pennsylvania

Application July 9, 1954, Serial No. 442,304

9 Claims. (Cl. 200—116)

This application relates to circuit breakers and discloses an improvement in the circuit breaker disclosed in Patents 2,374,778, issued May 1, 1945, to E. T. Platz; 2,385,727, issued September 25, 1945, to E. T. Platz; and 2,487,725, issued November 8, 1949, to E. T. Platz.

These patents disclose a circuit breaker having a push button type operation, which may be manually operated successively for opening and closing the circuit breaker contacts. The breaker is automatically operable for opening the circuit breaker contacts upon the occurrence of an overload current in the load circuit containing the breaker. The breaker includes in the operating mechanism a thermally responsive latch element which is manually engageable with, and automatically and manually disengageable from, a holding member in the mechanism. The overload rating of the breaker, i. e., the overload current value at which it is desired to have the circuit breaker open the circuit automatically, is determined by the degree of overlap of the latch portion of the thermally responsive latch element with the retaining portion of the holding member. Such circuit breakers are normally manufactured with a predetermined overload rating established by calibrating the breaker mechanism to obtain the appropriate degree of latching overlap between the thermally responsive latch element and the holding member. However, it is desirable to permit this calibration to be easily and quickly changed at times by an authorized person to increase the overload rating of the circuit breaker and thereby permit the load circuit to carry a higher value current when otherwise it would not do so. Additionally, it may be desirable to temporarily increase the latching overlap to thereby preclude release of the latch and separation of the contacts upon the occurrence of severe shock or mechanical vibration, such as that occurring on a battleship during the firing of the armament.

Accordingly, a principal object of this invention is to provide a circuit breaker which permits an increase in the predetermined overload rating.

Another object of this invention is to permit variation in the overload rating of a circuit breaker only by an authorized person.

Another object is to provide a circuit breaker in which the overload rating can be varied without altering the operating characteristics of the breaker.

Another object is to provide a mechanism in a latch type circuit breaker which enables an authorized person to selectively prepare the breaker for unusual shock or mechanical vibration.

Another object of this invention is to provide a circuit breaker in which the overload rating can be varied from the exterior of the circuit breaker housing.

Still another object of this invention is to provide a circuit breaker in which the overload rating can be varied by a simple, inexpensive mechanism.

Still other objects and features of the invention will appear from the specification and drawings in which:

2

Fig. 1 is an elevational view of a circuit breaker with the housing cover removed showing an embodiment of the invention disengaged from the circuit breaker mechanism.

5 Fig. 2 is a partial elevational view of a portion of the circuit breaker mechanism of Fig. 1 showing an embodiment of the invention engaged with the circuit breaker mechanism.

10 Fig. 3 is a partial cross-sectional view as if on line 3—3 of Fig. 1.

Fig. 4 is a partial cross-sectional view as if on line 4—4 of Fig. 1.

Fig. 5 is a partial cross-sectional view as if on line 5—5 of Fig. 1.

15 Fig. 6 is a partial cross-sectional view as if on line 6—6 of Fig. 2.

Fig. 7 is an exploded view of the circuit breaker handle showing the component parts of an embodiment of the invention.

20 Fig. 8 is an elevational view of the circuit breaker handle containing a modification of the embodiment of the invention shown in Fig. 1.

Fig. 9 is a bottom view of the handle shown in Fig. 8.

25 Referring to the drawings (Fig. 1), a circuit breaker, as disclosed in the hereinabove mentioned patents, includes a casing 10 of molded insulating material with the cover removed. Extending through the rear wall of this casing 10 is a line connector (not shown), having secured thereto a fixed contact 11 and a load connector 12 (not shown). Formed in the rear wall of casing 10 are grooves (not shown) in which an operator 12, comprising an embodiment of the invention which will be hereafter described, is slidably disposed. These grooves, in conjunction with the cover of casing 10, serve to guide

30 and position the operator 12 in its inward and outward movement. Beneath operator 12, with one end extending into a recess thereof, is a handle return spring 14, the opposite end of which is seated on an abutment extending from the rear wall of casing 10. Also positioned below operator 12 and adjacent to the rear wall of the casing 10 (Fig. 1) and arranged to be engaged by an extension 15 of the operator 12 when the breaker mechanism is in the open circuit position is a support member 16. Extension 15 upon inward movement of

35 operator 12 engages extension 17 of support member 16 to prevent lateral movement of support member 16 and imparts the operating force applied to operator 12 to the circuit breaker mechanism. Support member 16 has a cutout portion 18 which defines a latch surface

40 19. A composite member 20, having a pivot pin 21, is journaled in an opening in the lower portion of support member 16. This composite member 20 includes a bimetallic latch 22 having a turned down latching hook 23, a fixed contact 24, and a guide lug 25 which

45 abuts the upper surface of support member 16 to thereby determine the degree of overlap of latching hook 23 with latching surface 19 of cutout 18 of support member 16. A mainspring lug 26 receives one end of mainspring 27 which has the opposite end seated in the lower part

50 of casing 10 at 28. Mainspring 27 provides circuit opening and circuit closing force upon actuation of the breaker mechanism to these positions. Mainspring 27 also biases composite member inwardly against support member 16 to the extent permitted by the engagement of

55 guide lug 25 with the upper surface of support member 16 when the circuit breaker is in the closed circuit position, shown in Fig. 1.

Secured to the upper end of bimetallic latch member 22 is a flexible conductor 29 which connects the latch member 22 with a load connector (not shown).

60 Referring now specifically to operator 12 (Figs. 2 and 7) which comprises a rear half 31, a front half 32, adapt-

70

ed to be secured together by bolts 33, which are inserted through holes 34 and fastened by nuts 35. Rear half 31 and front half 32 are formed with recesses 36 and 37, respectively, which form a key slot 38 (Fig. 5) when the halves 31 and 32 are assembled. Each recess is further concavely enlarged in the center to form a shaft opening 39 in key slot 38, as shown in Figs. 5 and 6. Each recess is further cut away on alternate sides to form camways 40 and 41, which incline downwardly and toward the centerline of shaft opening 39 to recesses 40a and 41a in rear half 31 and front half 32, respectively, as shown in Fig. 7. The middle portion of front half 32 is cut away to leave a stud 51 and a wall 52 which abut surface 53 at 54 and 55, respectively. The lower portion of rear half 31 includes a cam surface 59 which functions to actuate the breaker mechanism from closed circuit position to open circuit position, as described below. A chamber 56 (Fig. 4) is thus formed when rear half 31 and front half 32 are assembled. Disposed within this chamber is an overload latch 60 and an overload latch spring 71 (Fig. 7). Overload latch 60 is preferably made of insulating material and comprises an L-shaped member having a body portion 61, a leg 62 of less thickness than the body portion, and a pivot 63. Body portion 61 is beveled as shown in Fig. 7 to form a cam surface 64. Overload latch spring 71 is preferably constructed of spring steel formed in a U shape and having an upper leg 71a and a lower leg 71b. A journal hole 56 is provided in the front half 32 of operator 12 to receive pivot 63 of overload latch 60.

Operator 12 is assembled by positioning overload spring 71 around body portion 61 of overload latch 60 with the lower leg 71b abutting surface 61a of latch 60. Pivot 63 is then placed in journal 56 of the front half 32 of operator 12 and the upper leg 71a of overload latch spring 71 positioned outside lug 51 (Fig. 1). The rear half 31 and front half 32 are then secured together by bolts 33 and nuts 35.

To actuate overload latch 60 to increase the overload rating of the breaker, a key 82 is provided (Figs. 1 and 2). Key 82 is formed from a strip of metal, preferably steel, and comprises a handle 81 of circular shape, a shaft 82a having flat wing-like extensions 83a projecting laterally from the end (Fig. 6).

With overload latch 60 disengaged and the circuit breaker in the closed circuit position of Fig. 1 with key 82 removed, the breaker operates as follows: Upon manual actuation of operator 12, cam surface 59 of the rear half of operator 12 strikes latch hook 23 of bimetallic latch 22 and cams it outwardly to release latch hook 23 from engagement with latch surface 19. Composite member 20, upon release of latch hook 23, rotates counterclockwise about pivot 21 under the bias of mainspring 27 to separate movable contact 24 from fixed contact 11. Support member 16 moves to the right to position extension 17 beneath extension 15 of operator 12. To move the circuit breaker to the closed circuit position, operator 12 is again manually depressed, forcing support member 16 downwardly and rotating composite member 20 clockwise about pivot 21 until latch hook 23 engages behind latching surface 19 under the inward bias of mainspring 27. Upon release of operator 12, support member 16 moves upwardly and to the left to the position of Fig. 1, permitting composite member 20 to move upwardly under the bias of mainspring 27 to bring movable contact 24 and fixed contact 11 together.

Upon the occurrence of an overload current of sufficient magnitude, bimetallic latch 22 is heated to warp outwardly to release latch hook 23 from latching surface 19 of support member 16. The degree of overlap of latch hook 23 with latching surface 19 thus determines the overload rating of the breaker as it determines the extent to which bimetallic latch 22 must warp to release latch hook 23 from latching surface 19

and permit the breaker to move to the open circuit position.

If it is desired to increase the overload rating of the circuit breaker or prepare the breaker for shock, key 82, which is in possession of an authorized person, is inserted into slot 38 of operator 12 (Fig. 1) into abutment with cam surface 64 of overload latch 60 (Fig. 3). Key 82 is then turned counterclockwise. Extensions 83a of shaft 82a then follow camways 41 causing key 82 to move downwardly. The end of shaft 82a of key 82 forces overload latch 60 to rotate counterclockwise against the bias of spring 71 about pivot 63. Further rotation of key 82 to the position of Fig. 2 causes leg 62 of overload latch 60 to position itself above support member 16 and adjacent to latch hook 23 of bimetallic latch 22. Extensions 83a engage recesses 40a, 41a to maintain key 82 and overload latch 60 in this position.

Upon the occurrence of the rated overload, latch hook 23 will be released from latch surface 19 of support member 16 upon the warping of bimetallic latch 22 and will strike the inner surface of leg 62 of overload latch 60. Movement of the circuit breaker mechanism to the "off" circuit position is thus prevented. Greater overload will cause additional warping of bimetallic latch 22 to permit latch hook 23 to clear leg 62 of overload latch 60. The particular additional overload rating desired to be imposed on the circuit breaker can thus be controlled by varying the thickness of leg 62 of overload latch 60. If the breaker is subjected to severe shock or mechanical vibration, sufficient to release latch hook 23 from latch surface 19, opening of the breaker will also be prevented by overload latch 60.

When it is desired to have the circuit breaker function normally, key 82 is rotated clockwise to remove extension 83a from recesses 40a, 41a of operator 12 and permit overload latch 60 to rotate clockwise about pivot 63 under the bias of spring 71 to the disengaged position of Fig. 1. Key 82 is then withdrawn and the circuit breaker will function as originally calibrated.

Disclosed in Figs. 8 and 9 is another embodiment of the invention. In this embodiment an operator 90 comprises a unitary housing having disposed in a chamber formed therein overload latch 62 formed as in the preferred embodiment and a torsion spring 92. A pivot pin 93 is positioned in housing 91 and journals overload latch 62. Torsion spring 92 is positioned on pivot pin 93 and has one leg secured in a recess 94 and a right angle portion of the other leg positioned beneath the body portion of overload latch 62, as shown in Fig. 9. A slot 95 is cut through the top wall of housing 91 to permit the insertion of key 82. The operation of this embodiment to vary the overload rating of the circuit breaker is the same as in the preferred embodiment.

Now having described the invention, reference should be had to the appended claims for the scope thereof.

I claim:

1. In a thermal overload circuit breaker having a casing, a fixed contact, an operator slidably disposed in said casing, a mechanism including a support member actuatable by said operator, a composite member actuatable by said support member, said composite member including an electroresponsive latch element engageable with, and disengageable from, said support member upon successive operation of said operator, said operator including means engageable with said mechanism for selectively varying the predetermined overload rating of said circuit breaker, said operator comprising mating halves having a chamber to receive said means when disengaged from said mechanism.

2. In a thermal overload circuit breaker having a casing, a fixed contact, an operator slidably disposed in said casing, a mechanism including a support member actuatable by said operator, a composite member actuatable by said support member, said composite member including an electroresponsive latch element engageable with, and dis-

engageable from, said support member upon successive operation of said operator, said operator including means engageable with said mechanism for selectively varying the predetermined overload rating of said circuit breaker, said means including a resilient element, an overload latch biased thereby to remain in disengaged position, and an actuator insertable in said operator and engageable with said overload latch to thereby cause said overload latch to position itself in said mechanism.

3. In a thermal overload circuit breaker having a casing, a fixed contact, an operator slidably disposed in said casing, a mechanism including a support member actuatable by said operator, a composite member actuatable by said support member, said composite member including an electroresponsive latch element engageable with, and disengageable from, said support member upon successive operation of said operator, said operator including means engageable with said mechanism for selectively varying the predetermined overload rating of said circuit breaker, said operator comprising mating halves having a chamber to receive said means when disengaged from said mechanism, said means including a resilient element, an overload latch biased thereby to remain in disengaged position, and an actuator insertable in said operator and engageable with said overload latch to thereby cause said overload latch to position itself in said mechanism.

4. For use with a circuit breaker, a variable overload mechanism including a resilient member, an overload latch member biased thereby to remain in a first position, an actuator engageable with said overload latch member to thereby actuate said overload latch member to a second position, a latch means engageable with said actuator to latch said overload latch member to said second position against the force of said resilient member, said resilient member causing said overload latch member to return to said first position upon disengagement of said actuator from said overload latch member.

5. For use with a circuit breaker, a variable overload mechanism including a manual operator having a chamber formed therein, an overload latch member and a resilient member disposed in said chamber, said resilient member biasing said overload latch member to remain in a first position, an actuator insertable into said operator to engage said overload latch member to thereby actuate said overload latch member to a second position, said resilient member causing said overload latch member to return to said first position upon disengagement of said actuator from said overload latch member.

6. For use with a circuit breaker, a variable overload mechanism including a manual operator having a chamber formed therein, an overload latch member and a resilient member disposed in said chamber, said resilient member biasing said overload latch member to remain in a first position, an actuator insertable into said operator to engage said overload latch member to thereby actuate said overload latch member to a second position, said resilient member causing said overload latch member to return to said first position upon disengagement of said actuator from said overload latch member, said manual operator comprising a first half and a second half, each half having complementary cam formations to form a camway to cause said actuator to move downwardly to move said overload latch member upon rotation of said actuator in said operator.

7. In a thermal overload circuit breaker having a manual operator, a bimetallic latch member, retaining means

engageable by said latch member to maintain said circuit breaker in a closed circuit condition, said bimetallic latch member warping upon rated overload to free itself from said retaining means to permit said circuit breaker to move to the open circuit position, and means disposed in said manual operator and actuatable from without said circuit breaker to move said means adjacent to said latch member to thereby selectively increase said overload rating of said circuit breaker.

10 8. A thermal overload circuit breaker being comprised of a pair of cooperating contacts, a casing, an operator, a support member, a composite member, an actuator; one of said cooperating contacts being secured to said casing; said operator being slidably mounted in said casing; said support member being actuatable by said operator; said composite member being actuatable by said support member; said composite member including the other of said cooperating contacts and an electroresponsive latch element engageable with, and disengageable from, said support member upon successive operations of said operator; said operator including a resilient element, an overload latch and a chamber; said overload latch being disposed in said chamber when biased to an inoperative position by said resilient element; said actuator being insertable in said operator and engageable with said overload latch to position said overload latch adjacent to said electroresponsive latch element and thereby increase the rating of said circuit breaker by a predetermined amount.

9. In a thermal overload circuit breaker having a casing, a fixed contact, an operator slidably disposed in said casing, a mechanism including a support member actuatable by said operator, a composite member actuatable by said support member, said composite member including an electroresponsive latch element engageable with, and disengageable from, said support member upon successive operation of said operator, said operator including means engageable with said mechanism for selectively varying the predetermined overload rating of said circuit breaker, said operator comprising mating halves forming a chamber and a recess, said chamber receiving said means when disengaged from said mechanism, said means including a resilient element, an overload latch biased thereby to remain in disengaged position, and an actuator insertable in said operator and engageable with said overload latch to thereby cause said overload latch to position itself in said mechanism, one end of said actuator being received by said recess and latched therein by the force of said resilient element when said means is in engagement with said mechanism; said actuator serving as an indicator for the position of said overload latch.
